BENDING MEANS FOR ROUND BAR IRONS

Lars Magnus Hedlöf and Karl Augustinus Hedlöf,
Stockholm, SwedenApplication May 1, 1948, Serial No. 24,648
In Sweden August 7, 1945

1 Claim. (Cl. 74—54)

1

The present invention relates to a bending machine for round bar-irons, with a bending table on which the iron to be bent is placed and retained by an abutment or the like during the bending around a bending shaft by means of a bending arm provided with a bending pin. The invention is characterized by a number of cams or cam disks fixed on a driven shaft, preferably a screw wheel shaft, each of said cams or cam disks being adapted to drive one of several carrier arms slidably mounted in a conventional manner on the bending shaft in different angular positions, said carrier arms being axially displaceable to coupling positions and provided with runners and adapted, after the coupling has been effected, to impart to the bending shaft a corresponding rotation until the runner has reached the top of the cam and goes clear of the same so that the iron placed on the table is bent to the desired angle in accordance with the number of cams which have actuated the bending shaft.

An embodiment of the device according to the invention is illustrated in the accompanying drawing, in which:

Fig. 1 and Fig. 2 show the device from two sides at right angles to each other. Fig. 3 is a top view of the device.

In the drawing the frame and the table are denoted by 1. In the frame are arranged a motor 2, a coupling 3 and a screw wheel casing 4. From said casing extends a screw wheel shaft 5 provided with a sleeve wedged on thereto and with five cams or cam disks 6 fixed on said sleeve, each of said cams or cam disks being adapted to drive one of several carrier arms 9 arranged on different vertically displaceable sliders embracing the bending shaft 8 in angular positions so that the different carrier arms 9 always extend in spaced angular directions, said sliders being displaceable by means of setting levers 7 to coupling positions wherein the carrier arms 9 on said sliders are in position to cooperate with the corresponding cam discs 6 on shaft 5. The carrier arms 9 are provided with runners 10 and adapted, after the coupling has been effected, to impart to the bending shaft a corresponding rotation until the runner has reached the top of the cam and goes clear of the same so that the iron 11 placed on the table is bent to the desired angle in accordance with the number of cams which have actuated the bending shaft.

In the plane of the table is swingably mounted a bending arm 12 fixed on the shaft 8 and provided at its one end with a bending pin 13. 55

There is also provided a rod 14 which is adapted to be actuated by a pedal, for example. At the upper end of said rod is located an abutment 15 or the like which is adapted to be depressed to the surface of the table against the action of a spring 16 fixed in a spring casing 17.

The device operates as follows. An iron 11 is placed between the abutment 15 and the shaft 8 whereafter the coupling is let in. By cooperation 10 between the motor 2, the coupling 3 and the screw gear in the casing 4 the screw wheel shaft 5 and the bending shaft 8 are set in rotation.

In the accompanying drawing the bending shaft 8 is provided with five carrier arms 9, denoted by a, b, c, d, e in the drawing. The cam shaft is provided with the same number of cam disks 6 denoted by a¹, b¹, c¹, d¹, e¹ cooperating with said carrier arms. Three of said carrier arms a, b, c may be connected to the bending shaft in such manner that they can cooperate with the respective cam disks a¹, b¹, c¹. The connection is effected by means of the upper setting or shifting lever 7 shown in the drawing.

The two remaining carrier arms, denoted by 15 d, e in the drawing are connected to the bending shaft 8 in such manner that they will be actuated by the cams d¹ and e¹ by means of the lower setting or shifting lever 7 shown in the drawing.

The drawing shows three carrier arms a, b, c 20 connected so as to cooperate with the cam disks a¹, b¹, c¹ or the number of carrier arms which need be actuated by three cam disks for such rotation of the bending shaft 8 that the iron 11 inserted between the support, the abutment 15 and the bending shaft 8 is bent 90°. It is also clear from the drawing that in the example chosen the cam disks d¹ and e¹ are not in a position on the shaft 8 to cooperate with the carrier arms d and e.

Thus, if it is desired to bend the iron to an angle of 45°, the carrier arm a is connected so 25 that the cam a¹ on the cam shaft 5 can drive the carrier shaft in question on the bending shaft 8 so as to move with its runner along the path of the cam until the runner has reached the top of the cam when it goes clear of the cam and is set out of function. After this operation has been finished, the cam b¹ has come to a 30 position to begin its operation and engages its corresponding carrier arm b which now performs its work. At the end of said two operations the bending arm 12 which lies in the plane of the table, has with its pin 13 carried along the iron. Said iron has now been bent to an angle of 45°.

The return of the bending arm 12 is effected automatically by coupling in a conventional way.

After finished bending, the arm 14 is depressed and thus also the abutment 15 whereafter the iron 11 easily can be removed.

Having now described our invention, what we claim as new and desire to secure by Letters Patent is:

In a bending machine for bar-irons comprising a supporting table, a bending shaft protruding above the surface of said table for receiving a conventional bending arm with a bending pin at the outer end thereof, and means for rotating said bending shaft, the combination of a number of axially displaceable sliders embracing said bending shaft in fixed angular position in relation to same, each having at least one carrier arm laterally projecting therefrom, all of said carrier arms having a runner at its outer end and being axially and angularly spaced relatively to each other, a driving shaft parallel to said bending shaft having a number of axially and angularly fixed and spaced cam discs adapted to cooperate with said runners at the outer ends of said carrier arms for transmitting rotative movement to said bending shaft, and means for axial dis-

placement of said sliders along said bending shaft for putting said carrier arms in and out of contact with their corresponding cam discs on said driving shaft.
